ELECTRIC SWITCH

Patrick J. O'Brien, Yeadon, Pa.

Application April 9, 1938, Serial No. 201,166

11 Claims. (Cl. 200—169)

This invention relates to electrical switches, and more particularly to switches of the type wherein the switch blade is clamped to the contacts with which it is associated when in its operative position.

An important object of the present invention is the provision in a construction of this character of an arrangement whereby a clamp-operating mechanism associated with the switch serves at the same time as a portion of the switch-blade-operating mechanism and is positively locked against movement into or out of clamping position until the switch blade has first been moved to its operative or contact-engaging position.

13 A further object of the invention is the provision in a construction of this character of a simple link and lever arrangement which, without the aid of external latches or the like, serves to hold the clamp-operating elements against 20 operation except when the switch is in its contact-engaging position.

A further object of the invention is the provision of a structure of this character which is readily adaptable to either stick or group operation.

25 These and other objects I attain by the construction shown in the accompanying drawings wherein, for the purpose of illustration, I have shown a preferred embodiment of my invention 30 and wherein:

Fig. 1 is a longitudinal sectional view through one form of switch embodying my invention;

Fig. 2 is a plan view thereof;

Fig. 3 is a section on line 3—3 of Fig. 1;

35 Fig. 4 is a detail view showing the position of the control mechanism after the clamps have been released;

Fig. 5 is a plan view of the mechanism when in the position shown in Fig. 4;

40 Fig. 6 is a sectional view showing positions of the parts when the switch is in its opened position;

Fig. 7 is a detail view showing the adjustment of the clamping elements;

45 Fig. 8 is a side elevation of a second form of switch embodying my invention, the switch being shown in closed position;

Fig. 9 is a plan view of the switch of Fig. 8;

Fig. 10 is an end elevation thereof;

50 Fig. 11 is a detail view showing the clamp adjustment in this form of switch;

Fig. 12 is a detail side elevation showing the position of the parts when the clamps are released;

55 Fig. 13 is a similar view showing the position

of the parts when the switch is in its open position;

Fig. 14 is a longitudinal sectional view through a further switch embodying my invention;

Fig. 15 is a section on line 15—15 of Fig. 14; 5

Fig. 16 is a section on line 16—16 of Fig. 14; and

Fig. 17 is a detail view partially in section showing the switch of Fig. 14 in the open position. 10

Referring now to the drawings, and more particularly to that form of the invention shown in Figures 1 to 7, the numeral 10 generally indicates insulators bearing stationary contacts 11 and 11a equipped with the usual bus connections 15 12, 12a. A blade generally designated at 13 is pivoted to the contact 11 for rotation about an axis 14. In the present instance the stationary contacts 11 and 11a are each shown as comprising a pair of upstanding conductors, those of the contact 11 being apertured for the passage of the pivots 15, while those of the contact 11a have notches 16 opening through their upper ends to permit introduction of clamping pins 17. The pivot pins 15 and clamping pins 17 each comprise 20 a head 18 having a small locking pin 19 adapted to selectively engage in any of a series of openings 20 formed in the adjacent member of the blade 13, a shank 21 passing through the associated contact element and both associated members 13a, 13b forming the adjacent side of the blade and a threaded inner end 22 adapted for engagement with a nut element 23 presently to be described. The inner ends of the elements 15 and 17 at opposite sides of the switch are oppositely threaded. While the members 15 have been referred to as pivot pins, they act not only in this capacity but as clamping pins, as will hereinafter become obvious. 30

Pivotedly connected to the base 24 of contact 11 at 25 is a link 26, and pivotedly connected to the opposite sides of the blade element by pivots 27 which substantially align with the pivots 25 when the blade 13 is in its closed position illustrated in Fig. 1, are levers 28 the opposite ends 45 of which are pivotally connected to the link 26 at 29. Pivots 29 are axially spaced through a distance equal to the axial spacing between the pivotal axis 14 of the blade and the pivots 25. The adjacent inner ends 22 of the clamping pivots 15 and clamping studs 17 are engaged by the double nut elements 30, 30a embodying nuts 23, 50 these double nut elements having radial arms 31, 31a. The arm 31 of nut 30 is connected through a link 32 with an angular arm 33 upon one of 55

the links 28. The arm 31a of nut 30a is at present illustrated as having at its outer end an eye 34 for the reception of an operating stick, this construction being simply illustrative since other forms of operation of the arm might readily be resorted to, and a link 35 connects this arm to the outer end of the arm 31.

Assuming the parts to be in the position illustrated in Fig. 1, at which time the double nut elements and their associated clamping members 15 or 17 have clamped the blade elements 13a, 13b at the respective sides of the switch blade upon the associated stationary contacts, if pressure be applied to the arm 31a in an attempt to open the switch, the switch is held in its locked position until the parts have moved to the position shown in Fig. 4. This is due to the fact that in order for the switch blade to move the links 26, which, in the position of Fig. 1, have their pivots 29 out of alignment with the pivot 14 of the switch forming a positive lock against switch movement, these links must first be moved to bring pivots 29 and 14 into alignment. Accordingly, the only movement which can be imparted to the switch structure at this time through pressure applied to arm 31a is a rotation of this arm, which rotation, through link 35, is imparted to arm 31 and through link 32 to the link assembly 26, 28, oscillating this assembly about the pivots 25, 27 until the pivot 29 aligns axially with the pivots 15. This rotation imparts a simultaneous rotation to the double nut assemblies 30, 30a releasing the clamping action of the clamps, following which the switch blade may rotate about its pivot to the position shown in Fig. 6. Due to the connection between links 28 and the arm 31 through link 32, and to the fact that this closing pressure is applied to the links 28 between the ends thereof, these links must rotate about their pivot 29 until the pivots 27 again align with the pivots 25. At this time the blade will be in its closed position and properly engage with its contacts, and further pressure applied will cause the double nut assemblies 30, 30a to rotate about their pivots and again clamp the same in position.

In the form of invention shown in Figs. 8 to 13, the stationary contacts 36 and 36a are unitary elements but otherwise correspond directly to the stationary contacts hereinbefore described. The blade 37 consists of a pair of spaced elements 37a, 37b adapted for engagement with opposite sides of the contact and but two clamping elements 38 and 38a are utilized. These clamping elements are identical in structure, each comprising a headed stud 39 having a lockable rotatable adjustment generally designated at 40, a shank 41 passing through both blades of the switch, and a threaded end 42 engaged by a single nut assembly 43. These nut assemblies are identical with the exception of the fact that that associated with the member 38a has an arm 44 for engagement with an operating member, each nut assembly having a pivot 45 for engagement with the end of a connecting link 46. Adjacent contact 36 and supported in the base thereof is a bracket 47 having a pivot 48 to which is connected one end of a link 49. Link 49, in turn, engages a pivot 50 the axis of which is spaced from the axis of pivot 48 a distance equal to the spacing of this axis from the axis of the switch axis 51 of the clamping blade pivot 38.

Secured to link 46 is an arm 52 the inner end of which bears pivot 50. Pivot 50 being affixed to the link 46, in common with the pivotal con-

nexion 45, must move through an arc parallel to the pivot 45 and it, accordingly, follows that the distance between centers of pivots 48 and 50 must be exactly the same as that between pivotal axis 51 and that of the associated pivot 45.

In this case the operation is substantially identical with that previously described. When pressure is applied to the arm 44 in an attempt to open the switch, the link 49 serves as a lock until link 46 has been moved longitudinally to bring the axis of pivot 50 into alignment with the pivotal axis 51. At this time, as seen in Fig. 12, the axis of pivot 45 is in approximate linear alignment with the axes of pivots 51 and 48. It will be seen that any further movement of pivot 45 about the pivot 51 as an axis must be as a result of turning movement of the blade 37 about the same pivot, for otherwise the pivot 45 would have to approach the pivot 50. Accordingly, during subsequent movement the pivot 50 remains in alignment with the pivot 51, the parts finally assuming the position shown in Fig. 13.

In return movement from the position of Fig. 13, if any longitudinal strain is placed on link 46 as will result in an attempt to close the switch, pivot 45 can only move from its final position while the pivot 50 remains in alignment with pivot 51, for obviously any movement of link 46 which is unaccompanied by a movement of the switch blade 37 will bring about the same circumstances, i. e., a recession of pivot 50 from pivot 48, which is prevented by link 49. The switch blade, therefore, moves to its closed position before there is any possible effective movement of the nut 43 with relation to the threaded portion 42 upon which it is mounted. After the blade is fully closed, longitudinal movement of link 46 is permitted and the clamps may thus be thrown into operation. In this form of the invention I preferably provide the link 49 and bracket 47 with coacting stop elements 49a, 47a which engage and check the movement of the link in the position shown in Fig. 12.

In the form shown in Figs. 14 to 17, stationary contacts 53, 53a comprise spaced members 54 between which the switch blade 55 is adapted to be disposed. The switch blade comprises spaced side elements 56 pivoted to the contact 53 at 57. These contact elements are connected intermediate their ends by a pair of spacing elements 58 each embodying a bearing 59 for a shaft 60. The ends of shaft 60 are connected by toggle links 61 to the side elements 56 of the blades, these toggle links being disposed in substantial alignment when the blade is in its closed position with the opposed elements constituting the stationary contacts 53 and 53a so that when the toggle links are properly actuated the blade elements 56 will move outwardly for forcible clamping engagement with the stationary contacts. Shaft 60 has an arm 62 connected thereto, the purpose of which will presently appear.

Pivoted to the base 63 of contact 53 at 64 are links 65 bearing pivots 66 which are equidistantly spaced from the pivot 64 with pivots 57. Bell 65 crank levers 67 are pivoted to links 65 upon the pivots 66 and are further pivoted to arms 68, affixed to the blade elements 56, by pivots 69 which, when the blade 55 is in closed position, substantially axially align with the pivots 64. An angular arm 70 on one of these levers is connected to the arm 62 of shaft 60 by link 71.

In this form of the invention I have illustrated the operating mechanism as a form which is obviously readily adaptable to the forms of the in-

vention previously described and is commonly employed in gang switches. This comprises the usual rotatable and insulated shaft 72 having an operating arm 73 to be connected to any suitable operating mechanism such as shaft 74 and actuating arm 75 linked to the upper ends of levers 67 as by link 76 and cross arm 77.

Assuming the parts to be in the position shown in Fig. 14, a pull upon link 76 cannot at this time move the blade 55 because of misalignment of the pivots 57 and 66. This initial movement, therefore, results in a mere pivotal movement of links 65 and levers 67 about their pivots 64 and 69 until these parts reach the dotted line position of said figure, at which time oscillation of the bell crank lever about the pivots 69 has rotated shaft 60 and through the toggles released the clamping engagement of the blade elements 56 with the contact members 54. Blade 55 then starts its rotation about pivots 57, finally reaching the position shown in Fig. 17. It will be noted that in this position there is a positive lock afforded by the positions of bell crank levers 67 and links 65 preventing any possible movement of the bell crank levers about their pivots 69 until the blade 55 has again returned to its closed position so that the clamping mechanisms are locked in their inoperative positions until the "switch closed" position is attained. Attention is further directed to the fact that owing to misalignment of the pivots when the clamping devices are in their clamping position, the switch blade itself is locked in its closed position. Considering, for example, the structure of Fig. 8, if an attempt is made to open the switch without moving the clamping elements to their open position, the link 48 will exert a downward strain on the link 46. This will tend to move the pivot 45 toward the pivot 50 which is, obviously, an impossibility.

While I have hereinbefore described all forms of the invention as including clamps at both the pivot and free ends of the switch blades, it will, of course, be understood that in some instances it may become preferable or even desirable to eliminate the clamp at the pivot end of the blade and to use simply a spring tension device for maintaining the proper contact between the blades and the pivot. In this event, of course, any rotatable member swinging about the pivotal axis of the blade may replace the corresponding clamping arm in the illustrated construction.

Since the constructions illustrated are, obviously, capable of considerable modification without any departure from the spirit of my invention, I do not wish to be understood as limiting myself thereto except as hereinafter claimed.

I claim:

1. In a switch, spaced stationary contacts, a blade pivoted to one thereof for engagement with the other thereof, a clamping device for the last-named contact carried by said blade for clamping said blade and contact to one another, a movable member carried by the blade and connected with said clamping device for actuating said device to open and close the same, and means to positively lock said member against movement when the blade is not in fully closed position, including a link pivoted to a stationary support adjacent the contact to which the blade is pivoted, an operative pivotal connection between said link and movable member, the last-named pivot being movable by the clamp actuating movement of the movable member into and out of axial alignment with the pivot of the

blade, movement of said movable member to close the clamp moving said last-named pivot out of axial alignment with the pivot of the blade.

2. A switch as claimed in claim 1 wherein the link is directly pivoted to the movable member.

3. A switch as claimed in claim 1 wherein the pivotal connection between the link and movable member comprises a lever pivoted to the blade, the pivotal connection of the link to the support and that of the lever to the blade being substantially in axial alignment when the blade is in its closed position.

4. A switch as claimed in claim 1 wherein the pivotal connection between the link and movable member comprises a lever pivoted to the blade, the pivotal connection of the link to the support and that of the lever to the blade being substantially in axial alignment when the blade is in its closed position, the movable member comprising a link shiftable longitudinally of the blade and a further link connecting said lever and the movable member.

5. A switch as claimed in claim 1 wherein the pivotal connection between the link and movable member comprises a lever pivoted to the blade, the pivotal connection of the link to the support and that of the lever to the blade being substantially in axial alignment when the blade is in its closed position, the movable member comprising a shaft rotatably supported by the blade, said shaft having an arm and a further link connecting the arm of the shaft and said lever.

6. In a switch, a stationary contact, a blade, a pivot connecting the blade and contact, a link pivoted to a fixed support at one end and having at its other end a second pivot movable into and out of axial alignment with the blade pivot, a second stationary contact for engagement with said blade, means to clamp said blade to said second contact including a rotatable clamping part, means to simultaneously rotate said rotatable clamping part about its pivot and to swing said link about its pivot on the fixed support, said second pivot of the link moving into axial alignment with the blade pivot as the rotatable clamping part is moved to released position, and a connection between the link and blade restraining rotation of the blade until said second pivot is axially aligned with the blade pivot.

7. In a switch, a stationary contact, a blade, a clamping pivot connecting the blade and contact and including a rotatable part coaxial with the blade pivot, a link pivoted to a fixed support at one end and having at its other end a second pivot movable into and out of axial alignment with the blade pivot, a second stationary contact for engagement with said blade, means carried by the blade to clamp said blade to said second contact including a rotatable clamping part, means carried by the blade to simultaneously rotate said rotatable clamping part about its pivot and to swing said link about its pivot on the fixed support, said second pivot of the link moving into axial alignment with the blade pivot as the rotatable clamping parts are moved to released positions, and a connection between the link and blade restraining rotation of the blade until said second pivot is axially aligned with the blade pivot.

8. A device as claimed in claim 7 wherein an operating means for said clamping parts and link comprises a rigid link connecting the clamping part and a member rotatable about the blade pivot and with which the second pivot of the first-named link is directly engaged.

9. A device as claimed in claim 7 wherein the rigid link connects the rotatable clamping parts and the restraining means comprises a lever engaged with the second pivot of the first-named link and pivoted to the blade and a third link connecting said lever and the second-named link.

10. In a switch, spaced stationary contacts, a blade pivoted to one thereof for engagement with the other thereof, a clamping device for each contact carried by said blade for clamping said blade and contact to one another, said contacts each comprising a rotatable clamping element, one of said clamping devices likewise constituting the pivot for the blade, the rotatable clamping element of the last-named clamp being rotatable about the axis of rotation of the blade, a link connecting said rotatable clamping elements and a second link pivoted at one end to a stationary

support and at its opposite end to the first-named link, said second link having its pivot axes spaced apart a distance equal to the radial distance between the pivotal axis of the blade and the axis of the pivotal connection between the associated rotatable clamping element and the first-named link, the pivotal connection between the first and second-named links lying between the pivotal axes of the rotatable clamping elements when said elements are in clamping position and axially aligning with the blade pivot when said elements are in released position.

11. A device as claimed in claim 1 wherein movement of the last-named pivot out of axial alignment with the pivot of the blade locks the blade in its closed position.

PATRICK J. O'BRIEN.
